UNITED STATES PATENT OFFICE.

FLOYD W. DE VINNEY, OF NUNDA, NEW YORK, ASSIGNOR TO THE FOOTE COMPANY, INC., OF NUNDA, NEW YORK, A CORPORATION OF NEW YORK.

DISTRIBUTING BUCKET FOR CONCRETE PAVERS.

Application filed May 8, 1926. Serial No. 107,590.

My invention relates to new and useful improvements in distributing buckets for concrete pavers, and the present invention is an improvement on a somewhat similar type bucket shown in Patent No. 1,562,751 of November 24, 1925.

The present invention, like its predecessor, above mentioned, relates broadly to a distributing bucket having pivotal bottom doors, a trolley supporting the bucket in its to and fro movement on the boom, a cross shaft on the trolley, a tripping mechanism in the form of a segment mounted on the shaft, and means extending from the bucket doors to the shaft, so that a rocking of the shaft by this segment will cause the doors to open and close as desired.

In addition to the above, the present invention also consists in the formation and arrangement of parts, wherein both doors may be automatically opened and closed, or the mechanism may be so arranged that only one door will automatically open and again, the parts may be so arranged that only one door will automatically open, but a handle or handles may then be operated, if desired, to also open the other door.

An object, therefore, of this invention is to provide a bucket supported by a trolley adapted to move to and fro on the boom, the trolley having a cross shaft on which is mounted a segment, which is indirectly connected to the doors of the bucket, so that the doors may be automatically opened or closed as in the patent above mentioned, and to provide further means wherein only one door may be opened automatically or wherein only one door may be opened automatically and the remaining door opened by hand.

Still another object of the invention is to provide a bucket with swinging doors at its bottom wherein the doors may be opened and closed together either automatically or by hand, or one door opened and closed automatically, the other door being capable of being opened by hand, and in addition, to provide means wherein the opening movement of one door with respect to the other may be adjusted, so that the discharge opening between the two doors may be arranged within certain limits.

Still another object of the invention is to provide a distributing bucket for concrete pavers, wherein the several doors are nor-

mally automatically operated, and wherein they may be operated by hand, if desired, and again wherein only one door may be operated automatically if a slower rate of discharge is desired.

With these and other objects in view, the invention consists in certain new and novel arrangements and combination of parts as will be hereinafter more fully described and pointed out in the claims.

Referring now to the drawings showing a preferred embodiment of my invention,

Fig. 1 is a side elevation of the bucket, the doors being shown in their closed position and a handle locked in position so that when the automatic door operating mechanism is operated, only one door will open.

Fig. 2 is an end view of the bucket and the trolley for supporting the same, and a section of the boom shown supporting the trolley.

Fig. 3 is a side view showing a fragmentary portion of the bucket and one of the doors in its opened position.

Fig. 4 is a similar view, but showing the door closed and the locking arrangement so positioned that when the automatic means for opening the doors is operated, both doors may swing to their open position.

Fig. 5 is a similar view, but showing the doors in their opened position.

Fig. 6 is a side view showing a fragmentary portion of the bucket, both doors being opened and the handle having been manually operated to open one of the doors.

Fig. 7 is a view on a reduced scale similar to Fig. 3, the adjustable means on the handle being moved so that one door is fully opened and the other door only partly opened, and Fig. 8 is a detailed section on line 8—8 of Fig. 6.

Referring now more in detail to Fig. 1, I have shown a fragmentary portion of a boom 1 on which travels the trolley 2, which in turn supports a bucket 3 through the provision of the hangers 4. In this trolley 2 is a cross shaft 5 on which is mounted the segment 6, and the stub arms 7, to which arms, in turn, are connected the off-set arms 8, which appear at the opposite sides of the bucket and in turn support the yoke rods 9. Compensating springs 10 are shown at the upper end of the yoke rods 9 to relieve any jars to the doors. The construction so far mentioned is all shown, described and

claimed in the patent to Charles E. Foote, No. 1,562,751 of November 24, 1925.

In the present application, a different form of means is shown extending between the yoke rods 9 and the doors 11 of the bucket, which arrangement will be shortly described in detail, but the means for operating the segment 6 by the cable 12, fragmentarily shown in the present application, is similar to the arrangement shown in the above mentioned patent, to wit, No. 1,562,751 and an earlier patent No. 1,443,454 of January 30, 1923, and another patent, No. 1,478,945 of December 25, 1923, so that a description of this part of the mechanism is not thought necessary. Suffice it to say, that an arresting of the cable 12 while the bucket is moving in either direction, will cause the segment to revolve to rock the shaft and either open or close the toggle and to open and close the doors of the bucket, depending upon the direction of travel of the bucket, and the position of the doors at the time the cable is arrested.

A handle 13 is shown mounted on the cross shaft 5 so that the toggle may be operated manually as well as automatically as in the former construction. In the present application, the bucket itself is slightly different from the bucket shown in the former patents in that the sloping forward and rearward ends are at such an angle that the doors 11 may be opened or closed without affecting the ground clearance.

On the opposite side of the bucket there are provided similar frames 14 for the support of the doors, these frames appearing at the lower portions of the sides.

Referring now to Figs. 2 to 6 inclusive, where the frames of the doors are shown on a larger scale than in Fig. 1, it will be seen that secured to the two doors 11 at their ends, are the two hangers 15, each of which is pivotally mounted in the casting or frame 14, as at 16. As before mentioned, the doors on their opposite ends will be likewise supported and the lower surfaces of the doors may be provided with the downwardly extending flanges 17 and the angle bars 18, which are suitably bolted into place.

Projecting from the lower portion of the hangers and adjacent thereto, are the small lugs 19, to each of which is pivotally secured a link. The link to the left, 20, being also pivoted at its upper end within the yoke of rod 9, while the link 21 is provided with a slot 22 at its upper end, the pivot pin 23 passing within the slot and also pivotally retaining the aforementioned link 20. Also pivoted to the lug 19 (on the door to the right) and at the lower end of the link 21 is the long handle 24.

Although I have only described the several links, hangers and handles on one side

of the bucket, it is to be remembered that the arrangement is identical on the opposite side of the bucket.

In the handle 24, there is shown a cut out portion 25 in its lower edge, and fastened about this handle there is shown a plate 26 with the large hole 27 near its lower end, while a plurality of small holes 28 are shown near its upper end, so that a bolt 29 may be passed through one of these openings 28 and a hole in the handle, so that the forward end 30 of the plate may be moved and set with respect to the edge 31 of the cut out portion 25 in the handle. The purpose of this will be shortly described.

To understand the various ways in which the doors may be opened and closed, it can be best understood by first referring to Fig. 4. In this figure, the handle 24 is shown as pinned or locked in a substantially upright position by the pin 23 being passed through the opening 27 in the plate. In this Figure the doors are shown in their closed position and if the segment and toggle (Fig. 1) is operated, the yoke rods 9, of course, will be lowered and both doors will swing to their farthest open position as shown in Fig. 5, as the handle 24, it will be remembered, is pinned in the yoke rod 9 and the slotted link 21 does not function except in conjunction with the handle. A return of the segment and a closing of the toggle (Fig. 1) will again pull the doors to their closed position.

As before mentioned the rocking of the segment may be done automatically or by the handle 13.

Of course, when the toggle is broken, the weight of the contents of the bucket will force the doors open, and in the arrangement just described, the bucket will be emptied quickly as the bottom doors are both allowed to swing to their full open position.

Referring now to Figs. 1 and 3, the handle 24 in this instance is shown as swung or dropped downwardly and the cut out portion 25 and the lower edge 30 of the plate abut a small pin 32 positioned at the pivotal point of the hanger for the left hand door.

If the toggle is broken one of the doors 11 to the left may swing to the position shown in Fig. 3 as the yoke rod 9 lowers but the handle 24 in this instance, which it will be remembered is secured to the lug on the door hanger at the right, being locked over the pin 32, the link 21 cannot move downwardly and the door to the right will be held in its closed position as clearly shown in Fig. 3.

The pin 23 of the yoke rods 9, of course, will travel down the slots 22 as the door to the left swings open, which may also be clearly seen in Fig. 3. When the handle is

locked as above described, and the toggle broken, the bucket will now discharge at half the rate than it did in the former instance where both doors are allowed to 5 swing to their open position.

Keeping in mind Fig. 3, and supposing it is desired for some reason when the bucket is discharging at half its rate, to open the other door, the handle 24 would be slightly 10 raised; in fact, the operator would stand in back of the bucket and slightly raise both handles 24 and they would then be freed from the locking arrangement and would 15 assume the position shown in Fig. 6, thus allowing the other door to swing open and the slotted link 21, of course, travelling on the pin 23. In other words, the length of the handle 24 from the pivotal point 19 to the locking pin 23 is now longer than the 20 length of the slotted link 21.

A closing of the toggle will automatically close both doors as shown in Fig. 1.

As far as the description has proceeded, it will be seen that the arrangements of the 25 doors and their parts are such that both doors may be opened or closed as desired, or only one door may be opened and further that if one door is opened and the other held closed, this may also be opened by a 30 shifting of the handles.

There is one more arrangement which might be put into effect, and that is the amount of swing of the door to the right may also be regulated by a movement and 35 setting of the plate 26 along the handle 24. In Fig. 7 I have shown the plate moved upwardly on the handle 24, thus in reality lengthening that part of the handle between the pivotal point 19 and the pin 32, and thus 40 allowing the door to the right to assume a partly open position, so that one door is all the way open and the other door is partly open, and in this manner, the bucket may be made to discharge at a slightly faster rate 45 than if one door only were open, and of course, less than if both doors were fully opened.

From the foregoing it will be seen that I have so constructed the bucket and its 50 door and the operating mechanism for the doors, that the rate of discharge of the bucket may be varied to suit the different requirements.

The arrangement is one which has proved 55 efficient in practice, is simple to operate and will withstand the hard usage incident to a device of this character.

Many slight changes might be made without in any way departing from the spirit 60 and scope of the invention.

Having thus described my invention, what I claim as new and desire to secure by Letters Patent is:—

1. A bucket for a concrete paver, a trolley 65 for supporting the bucket and adapted to

move to and fro on the boom, doors located at the bottom of the bucket, a toggle arrangement carried by said trolley and connected with the doors of the bucket, the doors arranged to swing towards and away 70 from each other, means connected with one of said doors and adapted to be secured to a part of the toggle arrangement whereby both of the doors will swing to an open or closed position on an opening or a closing 75 of the toggle.

2. A bucket for a concrete paver, means for supporting the bucket on a boom, a toggle mechanism carried by said means, swinging doors at the bottom of the bucket, links connected to the toggle mechanism to open and close the doors when said toggle mechanism is operated, handles operably connected to one of said doors and adapted to be secured to a part of the toggle mechanism to allow both doors to open and close when the toggle mechanism is operated, and the said handle also adapted to be lowered and secured to the pivotal point of the other of said doors to thereby allow only one door to open and close when the toggle mechanism is operated.

3. A bucket for a concrete paver having two swinging doors at its bottom, links at the opposite ends of the doors, toggle means for raising and lowering the links, the two links connected to one of the doors provided with slots, movable means pivoted to this same door adapted to be locked to said toggle means to thereby make the slotted links inoperable and allow both doors to open and close when the toggle is operated, and said movable means also capable of being locked in a lowered position to thereby permit only one door to open when said toggle is operated.

4. A distributing bucket for a concrete paver having two doors capable of swinging towards and away from each other at its bottom, links at the opposite ends of the door, means for raising and lowering said links, said links extending from one door being provided with a slot at their upper end and pinned to the means for raising and lowering the links, handles pivotally connected at their lower ends to the door provided with the slotted links, the said handles capable of being locked in their lowest position to thereby permit but one of the doors to open when the links are lowered, and said handles when raised slightly allowing the other of said doors to open and both of said doors being closed when the links are pulled upwardly.

5. In a bucket for a concrete paver, a pair of swinging doors at its bottom, links connected with the opposite ends of the doors, the two links connected to one of the doors each being provided with a slot at its

upper end, rods pinned to the links, means for raising and lowering said rods to thereby open and close the doors, handles extending from the opposite ends of the door which 5 is provided with the slotted links, said handles capable of being locked in a lowered position so that the portion of each handle extending between the one door and its locking point is shorter than the length of the 10 slotted links thereby allowing but one of the doors to operate when the rods pinned to the links are lowered, and said handles capable of being raised from their locked position to thereby lower the slotted links and 15 allow the other of said doors to open.

6. A concrete paver having swinging doors at its sides, links at the opposite ends of the doors, two of the links from one of said doors being slotted, pins passing 20 through the respective upper ends of said link and through respective rods for raising and lowering said doors, handles connected to the door provided with the slotted links and arranged to lock in one of two 25 positions, when locked in one position eliminating the slotted links from functioning to thereby cause both doors to open when the rods are lowered and when locked in the other of said positions allowing only one 30 of the doors to operate, and said handle adapted to be lifted from the latter position to thereby allow the other of said doors to open.

7. A discharge bucket for a concrete paver 35 having at its bottom pivotal and slotted links connected to the said doors, means connected to the link for raising and lowering the same, means in the form of handles pivotally connected to the opposite ends of one of said doors and arranged to be locked 40 in one position to thereby eliminate the slotted links when the links are lowered and permit both of the doors to open, and said handles also capable of being locked in another position to allow but one of the doors 45 to open and said handles when raised from the said locked position allowing the other of said doors to open.

8. In a concrete paver discharge bucket, 50 a pair of swinging doors arranged at its bottom, yokes at the opposite sides of the bucket, a pivoted and slotted link extending from each of said yokes, means for raising and lowering said yokes to operate said 55 links, handles capable of being locked in one position to prevent the slotted links from functioning when the yokes are lowered to thereby allow both of the doors to open, said handles also capable of being

temporarily locked in a lowered position to 60 allow but one of the doors to open, and said handles when raised from their temporarily locked position allowing the other of said doors to open, and means connected with the handles for regulating the amount of 65 opening of the last mentioned door.

9. A discharge bucket for a concrete paver having doors swingingly mounted at its bottom, pivotal links connected to one of said doors, slotted pivotal links connected to the 70 other of said doors, yokes on the opposite sides of the bucket pinned to their respective links, a toggle means for operating said yoke, levers pivotally mounted to the opposite end of one of said doors, said levers 75 adapted to be pinned to the yoke to thereby prevent the slotted link from functioning and allowing both doors to open when the toggle is operated, said levers also capable of being locked in a lowered position to 80 allow the slotted links to operate to thereby permit but one of the doors to open, and said levers when slightly raised from their latter position allowing the other of said doors to open, and means movable along 85 said handle and capable of being locked in a set position to thereby regulate the amount of opening of one of said doors.

10. A discharge bucket for a concrete paver, a trolley for supporting the bucket 90 and adapted to move to and fro on a boom, a cross shaft on said trolley, said cross shaft adapted to be manually and automatically operated, a toggle arrangement on said shaft, swinging doors at the bottom of the 95 bucket, links and yokes connected to said doors and to said toggle arrangement for operating said doors, regulating means connected with said doors and cooperating with said links whereby both of the doors may 100 be opened and closed on the operation of said toggle and whereby but one of said doors only may be opened and closed, and said regulating means determining the amount of movement of one of said doors. 105

11. A bucket for concrete pavers provided with swinging doors at its bottom, a link and yoke mechanism connected with the doors and a toggle arrangement operably connected with said yoke, one of said links 110 being slotted, a regulating means whereby both doors may be automatically opened together, one door may be automatically opened and whereby the other said door may be manually opened when the same has 115 not been automatically opened.

In testimony whereof I affix my signature.
FLOYD W. DE VINNEY.
